UNITED STATES PATENT OFFICE.

NICHOLAS J. CONRAD, OF WILMETTE, ILLINOIS, ASSIGNOR TO SCHWEITZER & CONRAD, INC., OF CHICAGO, ILLINOIS, A CORPORATION OF ILLINOIS.

FUSE.

Application filed May 17, 1926. Serial No. 109,814.

My invention relates to fuses, particularly to the type such as disclosed in Conrad Patent 1,220,152 of March 20, 1917, or Schweitzer & Conrad Patent Number 1,319,907 of October 28, 1919, in which type a transparent housing usually in the form of a glass tube is used for enclosing the fuse and circuit rupturing parts and the arc extinguishing liquid.

10 Glass is a very desirable material for enclosing the circuit controlling parts of the fuse structure as it has the necessary mechanical strength, is sufficiently electrically resistant, resists chemical attack by 15 the arc extinguishing fluid, and is transparent so that the contents of the glass housing can always be observed. Heretofore, plain uncolored glass has been used and such uncolored glass has disadvantages 20 which it is the important object of my present invention to overcome. Arc extinguishing fluid, particularly carbon tetra chloride has a tendency to attack substances, particularly metal, and such action is greatly increased in the presence of light. The fuses to which my invention apply are used in connection with high voltage transmission lines where the transformer or substations are out in the open so that the fuses are 25 fully exposed to the weather and to full sunlight. This intense light can readily pass through the uncolored glass and will hasten deterioration of the arc extinguishing fluid and its action on metals and other 30 substances within the fuse structure. The chemical or actinic rays of light are the ones which cause such action of the fluid, such rays pass readily through uncolored glass.

I have found that by using colored glass, 40 as for example, green, red, orange, or ruby colored glass, these chemical or harmful rays are intercepted and prevented from influencing the arc extinguishing fluid.

In order to illustrate the application of 45 my invention I have shown a fuse structure on the accompanying drawing. On the drawing,

Figure 1 is a side elevational view of a fuse structure partly in vertical diametral section; and

50 Fig. 2 is a top view.

Briefly describing the structure, 1 represents the enclosing glass tube which has at its lower end the terminal cap 2 and at its upper end the terminal cap structure 3, these

cap structures being rigidly sealed to the tube end. The lower cap structure has the axial lug 4 which is threaded to receive the lower terminal post 5 in which is secured the lower end of the flexible conductor 6. 60 Slidable in the tube at the upper end thereof is the annular plunger 7 to which the upper terminal post 8 is secured as by means of radial pins 9 extending therefrom into the plunger. The conductor 6 is secured in 65 the lower end of this upper terminal post. The tension spring 10 is anchored by means of pin 11 to the collar 12 which is secured to the lower terminal post 5 as by means of a screw 13. At its upper end the spring is 70 secured by pin 14 to the collar 15 which is secured by screw 16 to upper terminal post 8.

On the interior annular shoulder 17 formed on the terminal cap 3 above the end of the tube 1 rests the annular support 18 75 for the washer 19, this washer being of insulating material such as bakelite. The upper end of the upper terminal post 8 extends into and is slidable in the washer 19 and has the diametral slot 20 for receiving the 80 fuse structure 21 which is secured at its diametrical opposite ends to the cap structure 3 by means of the screws 22. This fuse structure may be of the type disclosed in my co-pending application Serial No. 32- 85 740 filed May 25, 1925, and normally holds the upper terminal post 8 in its upper position against the pull of the spring 10. Above the fuse structure the annular recess 23 in the cap structure 3 seats the vent cover 90 24 which with the adjacent walls of the cap structure 3 forms the explosion chamber 25 above the fuse structure. The tube 1 is filled with arc extinguishing fluid 26 such as carbon tetra chloride and this liquid 10 95 normally extends up to the washer 19.

The fuse structure is placed in service with its terminal caps in engagement with the terminals of a circuit to be protected, and upon abnormal current flow through the circuit, the fuse structure 21 will fuse and the upper terminal post 8 will be released whereupon the spring 10 will forcibly draw down the upper terminal post and with it the plunger 7. The plunger has the annular 105 convergent or nozzle passageway around the upper terminal post so that when the plunger is forcibly suddenly drawn downwardly in the tube 1 the extinguishing fluid will be squirted upwardly violently to effectively ex- 110

tinguish and destroy any arcing which might tend to take place after rupture of the fuse structure and downward movement of the upper terminal post.

5 Some fluids, as for example, halogen derivatives of hydro-carbon, and particularly carbon tetra chloride, have a tendency to attack metals and other materials and this action is greatly increased and hastened in 10 the presence of strong light. Where the fuses are placed in dark places, such action is not so noticeable, but fuses of the types described are used in outdoor substations or transformer stations and are exposed directly to strong sunlight, and under such 15 conditions of service a fluid such as carbon tetra chloride is under a disadvantage, and the increased activity in attacking materials in contact therewith and its tendency to dis- 20 integrate, detract from the efficiency and reliability of the fuse structure. The actinic or chemical rays of light are the ones which cause such action of the fluid, and where the glass of the surrounding tube 1 is un- 25 colored, these rays may readily pass through. Other material besides glass could be used which could keep out light entirely, but glass on account of its transparent quality is very desirable as it permits inspection of the fuse 30 working part at all times. I therefore make it possible to retain the use of glass and to still protect the contained fluid against the actinic rays of light by using colored glass or by applying coloring material to the pri- 35 marily uncolored glass. I find that with

green, red, orange, or ruby colored glass the actinic rays will be sufficiently intercepted or rendered harmless, although there may be other colors which will serve the same purpose. Such coloring will not interfere 40 with vision through the glass for inspecting the interior of the fuse structure at any time. The association of a color medium with the fluid will protect it even in the strongest sun or other light. 45

Having described my invention, I claim as follows:—

In a device of the class described, a pair of fuse terminals, a fuse element connected between them, a spring for moving one of 50 said terminals away from the other when the fuse melts, a fluid tight casing for said element, said casing including a pair of external terminals and an intermediate glass tube within which the spring is disposed, a bath 55 of arc extinguishing liquid in said casing, said arc extinguishing liquid comprising a halogen derivative of a hydrocarbon which is normally inert, but which, under the action of light, disintegrates and attacks the fuse, 60 changing its capacity, said glass tube having embodied therein a substance which screens out the rays that tend to disintegrate the liquid, but permits sufficient visible light to pass therethrough to permit the position of 65 the spring to be seen to determine whether the fuse has blown or not.

In witness whereof, I hereunto subscribe my name this 15th day of May, 1926.

NICHOLAS J. CONRAD.
